UNITED STATES PATENT OFFICE.

CHARLES V. SHORT, OF DES MOINES, IOWA.

SANITARY HEATED HOG HOUSE.

Application filed March 4, 1927. Serial No. 172,861.

The primary object of this invention is to provide an improved construction and arrangement for a hog house and particularly to provide improved means for dividing the interior of the house into a plurality of pens, each communicating with a smaller pen within a central polygonal space for the little pigs only, which space is provided with heating means.

10 A further object of this invention is to provide improved means for subdividing the interior of a hog house into a plurality of pens for farrowing purposes by means of a minimum number of partition members 15 which also cooperate to provide a central polygonal space arranged to communicate with each of the main pens and within which an improved means is provided for separating the little pigs of the various 20 litters.

A further object of the invention is to provide improved means for supporting the heating means in the central polygonal space.

25 A further object is to provide improved means for connecting a plurality of partition members so arranged as to form a plurality of main pens corresponding in number with the partitions, said partitions also 30 being arranged so as to form a central polygonal space, the number of whose sides corresponds with the number of partitions and main pens.

With these and other objects in view, my 35 invention consist in the construction, arrangement and combination of elements hereinafter set forth, pointed out in the claims and indicated by the accompanying drawing in which—

40 Fig. 1 is an exterior view of a hog house embodying my improvements.

Fig. 2 is a horizontal section on an enlarged scale on the line 2—2 of Fig. 1 and illustrating particularly the arrangement of 45 partitions to form a plurality of main pens and a central polygonal space.

Fig. 3 is a vertical section on the line 3—3 of Fig. 2 on a further enlarged scale and also illustrating the means for dividing the 50 central polygonal space.

Fig. 4 is a perspective view of the support for the heating means.

Fig. 5 is a perspective view illustrating the assembly of perforated partitions for 55 dividing the central polygonal space.

Fig. 6 is a perspective view of the platform which is supported within the central polygonal space.

Fig. 7 is a perspective view of one of the main partitions.

In the construction of the structure as shown, a housing of any suitable size and shape may be employed but I prefer to use a building having a substantially circular side wall 10 with a floor 11 and a substantially conical roof 12 provided with a ventilator 13. The building may be mounted on skids 14 if desired as shown in Fig. 1 so that it may readily be moved to various locations for use. The house so formed may be provided with any suitable number of doors 15 and windows 16, the doors and windows preferably corresponding in number and location with the main pens of the building as hereinafter described.

I have provided removable means for dividing the interior of the hog house into a plurality of pens, each arranged to receive a sow and her litter at and following the time of farrowing and also to form a central polygonal space, the number of whose sides corresponds with the number of main pens. The main partitions have a peculiar arrangement whereby a given number of such partitions serves to subdivide the interior of the building into an equal number of main pens and also to form the central polygonal space of a corresponding number of sides, said central space being also subdivided into a corresponding number of small pens to receive the little pigs only from the main pens with which they respectively communicate.

Each of the main partitions is constructed substantially as shown in Fig. 7 and preferably there are six of these partitions, each designated generally by the numeral 17. Each partition 17 is formed of a number of spaced boards 18 extending the full length of the partition and connected by vertical cross members 19 and 20 at their ends and a vertical cross board 21 between their ends but nearer the cross board 20 than to the board 19. Arranged below the longitudinal boards 18 is a board 22 which extends only from the cross board 19 to the intermediate cross board 21 thereby leaving a relatively low opening beneath one end portion of the lowermost board 18 which I have designated by the numeral 23. Each

partition 17 is arranged with one end abutting and detachably connected to the interior of the wall 10 and with its opposite end abutting the next successive partition 17 at a point adjacent its intermediate cross member 21 as clearly shown in Fig. 2. Each partition may also be provided with diagonal braces 24 extending between the cross members 19 and 21.

10 It is evident that where more than four partitions 17 are used they will engage each other at oblique angles to form main pens of irregular shape, each having an outer wall formed by a segment of the wall 10 and two inner walls, one formed by the full length of one partition 17 and the other formed by a portion of the length of the next succeeding partition in the series. It is also apparent that this arrangement of the partitions will form a central polygonal space having a number of sides corresponding to the number of partitions and each side composed of a portion of one of the partitions. In other words, the sides 25 of the central polygonal space are formed by those portions of the partition 17 between the cross members 20 and 21 and access is had to such central polygonal space by means of the opening 23 of each partition.

30 As here shown, there is a hook 25 fastened to the outer upper corner of each partition 17 which is adapted to engage the eye of an eye bolt 26 extending through the wall 10 of the building. A pivoted button 27 may be mounted on the wall 10 to engage the upper side of the gate or the hook 25 and prevent accidental displacement thereof when the partitions are assembled. When the partitions are all assembled their inner 35 end portions engage and support each other in such manner that a stable structure is formed but additional means may be provided for connecting them at the corners of the central polygonal space if desired. I have shown each partition 17 provided with a cleat 28 on its inner face against which the inner end of another partition 17 may engage to prevent such inner end being accidentally moved inwardly of the central 40 polygonal space.

45 The central polygonal space is subdivided into a plurality of small pens, each communicating through an opening 23 with one of the main pens and in Fig. 5 I have illustrated in detail the means for subdividing this central polygonal space. I have provided a plurality of sheet metal partitions 29, in this instance six in number, each formed at its outer end with a flange 30 adapted to be attached to one of the main partitions 17 by means of bolts, screws, or the like. Each partition 29 is bent at an angle at its inner end to form an inner end wall 31 which wall is formed with an attaching flange 32 at its end which is adapted 50 to contact with and be attached to the next succeeding partition 29 of the series, as by means of stove bolts or the like. The inner end walls 31 cooperate to form a polygonal space similar to the central polygonal space hereinbefore referred to and arranged concentrically thereof and this smaller innermost space is designed to receive the support for the heating means. The support is shown particularly in Fig. 4 and it comprises an angle iron rim 33 of a shape corresponding to and adapted to be received within the innermost polygonal space, said rim having a plurality of supporting legs 34 adapted to rest on the floor. The rim 33 is supported at about the level of the tops of the inner end walls 31 and a pan 35, shown in Fig. 3, is adapted to be mounted thereon. Mounted in the pan 35 is a suitable heating means such as a brooder stove 36 adapted to supply heat to the central polygonal space and suspended above said stove is a conical hoover 37 of common form which may be adjustable vertically by its suspending means indicated by the yoke 38 and rope 39. 55 When the partition members 29 are rigidly secured to the main partition members by the attaching flanges 30 and to each other by the attaching flanges 32 of the inner end walls, a rigid structure is provided which 60 suitably divides the central polygonal space into a plurality of small pens for the little pigs and also forms the innermost space for the support for the heating means. The inner partitions 29 may be provided with 65 perforations 40 if desired but the inner end walls 31 are imperforate. This arrangement provides for ventilation of all the inner pens and also for uniform distribution of 70 artificial and body heat throughout said pens.

75 There is also a platform 41 (see Fig. 6), supported within the central polygonal space, which platform is similar in size and shape to the interior of said space and is provided with a central opening 42 for the stove 36. The upper margin of the platform 41 engages the inner faces of certain 80 portions of the main partition 17 and is supported by cleats 43 carried thereby. The platform 41 is also formed with a plurality of slots 44 extending outwardly from its central opening 42. A rod 45 has one end portion extending through a slot 44 and is provided with means 46 for engaging the lower face of the platform. The rods 45 extend upwardly and outwardly as clearly shown in Figs. 2 and 3 and at their upper ends are formed with hooks 47 which detachably engage in the eyes of eye bolts 48 extending through the partitions 17 and also as here shown through the cleats 28. In this manner the platform 41 is rigidly supported by those portions of the main partitions 17 which enclose and form the central polygonal 85 90 95 100 105 110 115 120 125 130 135

space and the platform serves to make more rigid the central structure formed by said partitions and to bind the partitions together.

The platform 41 preferably is arranged a material and considerable distance above the tops of the partitions 29 so that heat from the stove may radiate without interference to all of the central pens.

Each of the main pens is adapted to receive a sow and her litter and the little pigs may pass freely through the openings 23 to the inner pens where they will be protected from injury by the mother and also receive heat from the stove 36. As the openings 23 to the inner pens open off from the narrow pointed ends of the main pens, it is difficult for the mother to lie across and block said openings. The peculiar shape of the main pens, as provided by the particular arrangement of the main partitions here shown and described, is also of advantage in economy of space and maximum length of the sides of said main pens in providing accommodations for the larger animals which would not be possible unless the inner ends of the main pens lapped upon or extended past the central polygonal space.

The interior structure including the main partitions and the platform, heating means and inner partitions 29, may be readily removed at times when the building is desired for use as an ordinary hog house.

My new and improved arrangement provides for a minimum number of main partitions as only one main partition is required for each of the main pens to be provided. This greatly decreases the amount of material needed as well as the labor necessary in assembling and disassembling and also facilitates storage and transportation. The peculiar arrangement of the inner partitions 29 makes it easy to take them apart and to nest them together for storage and transportation. By making the inner partitions and the stove support of metal, I have lessened the fire hazard and added to the safety of the structure.

I claim as my invention:

1. A hog house comprising an outer wall and a plurality of partition members each having one end abutting the outer wall and the other end abutting an intermediate portion of the next succeeding partition of the series whereby to form a plurality of main pens and also to form a central polygonal space each side of which consists of a portion of one of said partitions.

2. A hog house comprising an outer wall and a plurality of partition members each having one end abutting the outer wall and the other end abutting an intermediate portion of the next succeeding partition of the series whereby to form a plurality of main pens and also to form a central polygonal space each side of which consists of a por-

tion of one of said partitions, each of said partitions being formed with a relatively low opening affording access from one of said main pens to said central polygonal space.

3. A hog house comprising an outer wall and a plurality of partition members each having one end abutting the outer wall and the other end abutting an intermediate portion of the next succeeding partition of the series whereby to form a plurality of main pens and also to form a central polygonal space each side of which consists of a portion of one of said partitions, partition means for dividing said central polygonal space into a plurality of relatively small pens, and an opening through each of said main partitions affording communication between one of the main pens and one of the small central pens.

4. In a hog house, a plurality of main partition members arranged to form a central polygonal space, each of said partitions being extended at one end only into contact with the wall of the house whereby to form a plurality of main pens, separate partitions arranged at angles to the first named partitions and dividing the central polygonal space into a plurality of relatively small pens, each of said small pens being adjacent to and extending at an angle from the inner end portion of one of the main pens and communicating therewith.

5. In a hog house, a plurality of main partitions arranged to form a central polygonal space, each of said partitions being extended at one end only into contact with the wall of the house whereby to form a plurality of main pens, a plurality of partitions dividing the central space into a corresponding number of relatively small pens each communicating with one of the main pens, and a platform supported on said main partitions and spaced above the upper margins of said inner pens.

6. In a hog house, a plurality of main partitions arranged to form a central polygonal space, each of said partitions being extended at one end only into contact with the wall of the house whereby to form a plurality of main pens, a plurality of partitions dividing the central space into a corresponding number of relatively small pens each communicating with one of the main pens, a platform supported on said main partitions and spaced above the upper margins of said inner pens, and a heating means supported at the center of said polygonal space independently of the inner partitions thereof.

7. In a hog house, a plurality of partitions forming a corresponding number of main pens and also forming a central polygonal space, a plurality of metallic partitions each connected at one end to one of the

- main partitions and having its opposite end portion bent laterally to form an inner wall adapted to engage the next succeeding partition of the series, a heater support arranged loosely within the central space formed by the inner end walls, and a brooder stove mounted on said support and adapted to provide heat for said central polygonal space.
8. In a hog house, a plurality of partitions forming a corresponding number of main pens and also forming a central polygonal space, a plurality of metallic partitions each connected at one end to one of the main partitions and having its opposite end portion bent laterally to form an inner wall adapted to engage the next succeeding partition of the series, a heater support arranged loosely within the central space formed by the inner end walls, a brooder stove mounted on said support and adapted to provide heat for said central polygonal space, and an annular platform surrounding said stove at a point above the upper edges of said metallic partitions and supported against the inner faces of said main partitions.

CHARLES V. SHORT.
